UNITED STATES PATENT OFFICE.

STEPHEN C. THORNING, OF MILWAUKEE, WISCONSIN.

DESIGN FOR A SAVINGS BANK.

Application filed August 14, 1922. Serial No. 3,386. Term of patent 3½ years.

To all whom it may concern:

Be it known that I, STEPHEN C. THORNING, a citizen of the United States, and residing at Milwaukee, in the county of Milwaukee and State of Wisconsin, have invented a new, original, and ornamental Design for Savings Bank, of which the following is a specification, reference being had to the accompanying drawing, forming part thereof.

The single figure is a perspective view of my savings bank.

I claim:

The ornamental design for a savings bank, as shown.

STEPHEN C. THORNING.

Witnesses:

E. C. GABEL,
LILIAN M. KOHLMETZ. L
